UNITED STATES PATENT OFFICE.

AUGUSTUS C. SAXTON, OF BETHEL, ASSIGNOR OF TWO-THIRDS TO JOHN DODD AND CHARLES F. SPENCER, OF DANBURY, CONNECTICUT.

AXLE-CUTTER.

SPECIFICATION forming part of Letters Patent No. 554,034, dated February 4, 1896.

Application filed May 28, 1895. Serial No. 550,936. (No model.)

To all whom it may concern:

Be it known that I, AUGUSTUS C. SAXTON, a citizen of the United States, residing at Bethel, in the county of Fairfield and State of Connecticut, have invented certain new and useful Improvements in Axle-Cutters, of which the following is a specification.

My invention relates to the class of hand-operated portable machines for cutting or trimming metal axle arms or spindles while the same are on the vehicle.

It is well understood by those who use wagons that the ends of the hub-boxes wear away from the access of grit between the stationary and rotating parts, thus necessitating the constant application of washers between said parts, as these latter also wear away rapidly. To obviate the looseness and endwise movement of the hub-box on the axle-arm, due to this shortening of the box by abrasion, it has been the practice, to some extent, to cut away the end of the arm so as to shorten it, and this requires, first, the cutting back of the shoulder or the arm where the latter is reduced to form the screw-threaded tip for the nut, then to cut off the end of said tip to the proper length, and then to continue the screw-thread on the tip down to the newly-formed shoulder. My machine effects all of these objects efficiently and rapidly, and it is simple in construction and easily operated by any one with very little experience.

In the drawings which illustrate an embodiment of the invention, Figure 1 is a longitudinal axial section of the machine, which is shown in place on the axle-arm or spindle of a wagon. Fig. 2 is an end view of the machine, showing the end seen at the left hand in Fig. 1. Fig. 3 is an end view showing the end seen at the right hand in Fig. 1. Fig. 4 is a transverse section taken on line $x^4 x^5$ in Fig. 1. Figs. 5, 6, and 7 are respectively a side view, face view, and plan of the cutter-head or tool-holder detached and showing also the screw-cutting dies in place therein. Fig. 8 shows the feed-screw detached, and Fig. 9 is a plan view of the feed-sleeve detached.

In the principal views, A represents the axle-arm which is being operated on. This axle-arm is clamped in a self-centering clutch

similar to that of a lathe, and comprising as its essentials a ring or frame 1 and clamping-jaws 2, mounted in said frame and furnished with bevel gear-wheels 3, fixed on screw-threaded spindles 4, mounted in the frame. These latter screw into and operate said jaws and a toothed rim 5 in the hollow of the frame-gears with the several wheels 3. The squared ends of the spindles 4 project from the frame and any suitable wrench 6 may be employed to set the jaws firmly on the axle-arm A. As all of the jaws 2 move simultaneously, they center the object clamped with respect to the ring-frame.

Mounted on the frame 1 are posts 7, preferably three in number, and fixed to these posts is a frame 8. Mounted in the frame 8 is a feed-sleeve 9, in which is rotatively mounted the arbor 10 of the cutter-head 11. The sleeve 9 is adapted to move endwise in the frame 8, but is prevented from rotating therein by a spline 12, and the arbor 10 is adapted to rotate in the sleeve 9, but is prevented from moving endwise or longitudinally therein by a screw or stud 13 set in the sleeve 9, its end or tip engaging a circumferential groove 14 in the arbor 10. On the outer end of the arbor is a square, adapted to receive a crank 10^a for rotating the cutter-head by hand.

The cutter-head 11 is adapted to receive and hold one or more cutters 15^{15X}, which are set in mortises in the wings on the cutter-head and secured therein by screws 16 when properly adjusted. When the arbor of the cutter-head is rotated, the sleeve 9, carrying the cutter-head and its arbor, is fed forward automatically by means I will now describe.

In the side of the sleeve 9 is a flute or shallow concavity extending lengthwise of the sleeve and having cut in it a screw-thread 9^X. (Seen best in Fig. 9.) Mounted rotatively in the frame 8 is a sleeve 17, in which is eccentrically mounted the arbor 18^X of a screw 18, adapted to engage the screw 9^X in the sleeve 9. This screw 18 is housed within a hollow part of the frame 8, and it may be depressed into gear with the screw 9^X, as seen in Fig. 1, or lifted out of mesh therewith, as indicated in Fig. 4, by a partial rotation of the sleeve 9. This partial rotation of said sleeve is effected

by means of a pin 19, set therein and playing in a guide-slot 20 in the inclosing frame. The mutilated screw 9^x is, in reality, only a series of teeth on the sleeve 9, and the screw-threads 5 may as well be a series of teeth. The construction shown, however, is strong and compact.

On the outer end of the arbor 18^x is secured a ratchet-wheel 21, and mounted to swing 10 radially about the said arbor is a pawl-arm 22, to which arm is pivoted a pawl 23, the nose of which engages the teeth of the ratchet-wheel 21. The pawl-arm extends down by 15 the arbor of the cutter-head (see Fig. 2) and is pressed up thereto by a spring 24, mounted on the frame 8. A spring 23^x on the pawl-arm keeps the pawl in engagement. When the arbor 10 is rotated, a longitudinally-extending feather or rib 25 thereon takes under the pawl-arm 22 and by pressing it outward advances the pawl, thus imparting a partial rotation to the ratchet-wheel. When this feather passes, the spring 24 retracts the pawl. This 20 intermittent rotation of the ratchet-wheel imparts, of course, the same movement to the screw 18, which thus feeds the sleeve 9 and the cutter-head during the cutting operation.

I will now briefly explain how the machine is used. The nut being removed from the 30 axle, the hub pushed back to the shoulder and the axle-arm marked to designate the amount to be cut away at the shoulder, the axle is supported and the wheel removed. The clutch of the machine is now passed over the arm 35 A—say to about the extent seen in Fig. 1—and the jaws of the clutch made to clamp on it firmly. The axle-arm will now be accurately aligned with the arbor of the cutter-head. The cutter 15 is now adjusted so that 40 its cutting-edge just clears the thread on the screw on the reduced end *a* of the axle-arm, the other cutter 15^x (if two be employed) being withdrawn or removed. Rotation of the cutter-head causes the cutter 15 to cut down 45 the shoulder *a*^x on the axle-arm back to the point desired. After cutting back the shoulder the screw 18 is disengaged by the pin 19, the cutter-head is drawn back to the starting-point, (the position seen in Fig. 1,) and the 50 cutter 15^x set into the axis of the machine for cutting down the tip *a* of the arm to the same extent as the shoulder.

After cutting down the axles of the vehicle as above described, it will be necessary to cut 55 the screw-threads on the ends *a* of the axle-arms down to the new shoulders formed. This will be done by the means I will now describe.

Referring to Figs. 5, 6 and 7, in a holder 60 26 is mounted a pair of screw-cutting dies 27, adapted to fit the standard-screw on axles. This frame has screws 28 for setting up the dies on the screw, and it is made to fit snugly in a seat between the arms on the cutter-head 11, where it is held, preferably, by a set-screw 29. In order to facilitate the placing of the 65 die-frame in its seat, a stop 30 is provided on the cutter-head, Fig. 5, to arrest the frame

when it is in place. This stop may be merely the projecting head of a screw, as here shown.

In cutting the screw the feed-screw will be 70 thrown out of gear, so that the dies may feed themselves in the usual way, proportionate to the pitch of the screw.

The camming-fin 25 on the arbor 10 is elongated in order that it may be in position to 75 act on the pawl-arm 22, whatever may be the position of the cutter-head.

Having thus described my invention, I claim—

1. In an axle-cutter, the combination with 80 a device for clamping on the axle-arm and a frame 8, secured to said clamping device, of the feed-sleeve 9, mounted in said frame and adapted to be moved to and fro therein, the cutter-head, the arbor of the cutter-head, 85 rotatively mounted in the feed-sleeve and stopped against longitudinal movement therein, a feed-screw, rotatively mounted in the frame 8 parallel with the arbor of the cutter-head and in gear with screw-threads or teeth 90 on the feed-sleeve, and a ratchet mechanism, intermediate the arbor of the feed-screw and the arbor of the cutter-head, whereby the cutter-head is fed up to its work automatically by the rotation of said head, substantially as 95 set forth.

2. In an axle-cutter, the combination with 100 a device for clamping on the axle-arm and a frame 8, secured to said clamping device, of the sleeve 9, mounted in a sliding bearing in 105 said frame and provided with teeth 9^x, the sleeve 17, rotatively mounted in the frame 8, the feed-screw 18, the arbor of which is eccentrically and rotatively mounted in the sleeve 17, with its axis parallel with the arbor 105 of the cutter-head, the pin 19, set in the sleeve 17, and adapted to play in a guide-slot in the inclosing frame, whereby the sleeve 17 may be rocked and the screw 18 be put into or out 110 of engagement with the teeth 9^x on the sleeve 17, the ratchet-wheel on the arbor of the feed-screw, the radially-swinging pawl-arm on said arbor, the spring-pawl carried by said arm and engaging the teeth of the ratchet-wheel, and the feather on the arbor of the cutter- 115 head, adapted to actuate the pawl-arm and pawl, substantially as set forth.

3. In an axle-cutter, the combination with 120 a self-centering clutch to clamp on the axle-arm and a frame secured to said clutch, of the cutter-head, having its arbor axially aligned with the clutch, of the feed-sleeve mounted in and adapted to slide in said frame and carrying the arbor of the cutter-head, a feed-screw, rotatively and eccentrically mounted 125 in a rocking sleeve 17 in the frame, said screw being adapted to engage teeth on the feed-sleeve, means for rocking said sleeve 17 to put the feed-screw into or out of gear with the feed-sleeve, and a ratchet mechanism, intermediate the arbor of the feed-screw and the arbor of the cutter-head for automatically feeding the latter, substantially as set forth.

4. In an axle-cutter, the combination with

a clutch device to clamp on the axle, a frame fixed to said clutch device, a cutter-head having its arbor aligned with said clutch device, a screw mechanism for automatically feeding 5 said cutter-head during the operation of cutting down the axle, means for throwing said feeding mechanism out of operative connection with the cutter-head during the operation of cutting the screw-thread on the axle, 10 and a die-frame and screw-cutting dies adapt-

ed to fit in a seat formed in the cutter-head, the latter being also provided with a seat to receive a cutter, substantially as set forth.

In witness whereof I have hereunto signed my name in the presence of two subscribing 15 witnesses.

AUGUSTUS C. SAXTON.
